TRIGGER MECHANISM

John G. Seitz, San Francisco, Calif., assignor to
Samuel I. Keene, San Francisco, Calif.

Application December 13, 1943, Serial No. 514,073

6 Claims. (Cl. 42—69)

This invention relates to a trigger mechanism for firearms, and has for one of its objects the provision of a trigger mechanism having means cooperatively associated therewith for quickly and easily varying the point in the oscillatory path of travel of the trigger at which the cocked cocking piece may be released.

Another object of the invention is the provision of a trigger mechanism having means for quickly and easily changing the characteristic of the trigger from one that is subjected to a prolonged frictional resistance before releasing the cocked cocking piece to one that is not subjected to such resistance and vice versa.

Another object of the invention is the provision of a trigger mechanism having means for quickly and easily changing the type of the trigger from one that effects a release of a cocked cocking piece during the retractive movement of the trigger to one that causes such release during the movement of the trigger from a fully retracted position to its normal forward position, and which mechanism further provides for changing the point during oscillatory movement of the trigger in one direction at which the said cocking piece is released.

A still further object of the invention is the provision of an improved safety device associated with a convertible trigger mechanism for manipulation and operation in a manner that makes accidental actuation of the said device from a "safety" to an "on" position or vice versa, practically impossible, and which safety device, when in the "on" position continues to function as a safety device when the trigger mechanism is adjusted for release firing, except when said device is actuated by the normal gripping pressure of one of the fingers of the hand that carries the trigger finger. However, a release of such pressure by such finger at any time prior to the release of the cocked cocking piece will render the trigger inoperative for effecting such release.

In my co-pending application for United States Letters Patent, Serial No. 508,773, filed November 3, 1943, I show one means for converting a trigger mechanism from "compression" to "release" type of firing. By "compression firing" I mean the conventional type wherein the cocked cocking piece (hammer, bolt, firing pin, etc.) is released during retractive movement of the trigger, while by "release" firing I mean the type wherein the cocked cocking piece is released during the return travel of the trigger from a fully retracted position to its normal forward position under spring tension.

Among users of small firearms there exist differences that have heretofore compelled such users to employ expert gunsmiths to modify standard structure. Most users that have tried the "release" type of trigger mechanism have a preference for that type, but long custom and the heretofore unavailability of the release type of mechanism has resulted in most users being acquainted with the "compression" type of trigger mechanism. These latter users are divided into two schools. One practices the slow "trigger squeeze" method whereby the user is not supposed to give consideration to the moment at which the movement of the trigger will release the cocking piece, and the other school advocates the use of a "hair trigger" or a slight modification thereof. My improved trigger mechanism provides a firearm that is almost instantly convertible to fulfill the requirements of an advocate of any one of the aforesaid schools, and which mechanism also provides for slight play of the trigger between fully retracted position and forward movement thereof before the cocked cocking piece is released when said mechanism is set for "release firing." By "slight" play or movement, I do not mean that the trigger is loose, but instead, I mean that the trigger may slightly be oscillated under alternate influence of a spring urging it forward and application of a superior retracting pressure by the trigger finger adjacent the fully retracted position of the trigger without causing a release of the cocking piece. This degree of oscillation is preferably no greater than about the thickness of a silver dollar or about a tenth of an inch or from .05 inch to about .1 inch. Anything substantially outside the above range is not wholly desirable for neurological, physiological and psychological reasons that have been established.

Other objects and advantages will appear in the description and drawings.

In the drawings,
Fig. 1 is a fragmentary side elevational view of the breech portion of a 1903 Model U. S. 45 Springfield rifle showing in elevation the manual controls for converting the rifle for different types of firing, and for safety.

Fig. 2 is a sectional view taken vertically through the breech portion of Fig. 1 longitudinally of the latter, certain parts being indicated in elevation for clarity.

Fig. 3 is a fragmentary part sectional and part elevational view of the trigger mechanism arranged for "release" firing, and showing the trigger fully retracted preparatory to its forward

movement and for causing a release of the cocked cocking piece.

Fig. 4 is a fragmentary part sectional, part elevational view of the trigger mechanism converted for compression firing of the "crisp" or modified "hair trigger" type.

Fig. 5 is a fragmentary sectional view showing the safety device adapted to render the trigger mechanism inoperative for "release" firing when the latter is locked in "safety" position.

Fig. 6 is a fragmentary enlarged sectional view taken along line 6—6 of Fig. 1.

Fig. 7 is a fragmentary sectional view taken along line 7—7 of Fig. 6.

Fig. 8 is a fragmentary plan view of a recessed plate in the wooden stock for receiving a rotatable adjusting disk.

Fig. 9 is an enlarged sectional view taken along line 9—9 of Fig. 1.

Fig. 10 is a fragmentary sectional view showing one of the positions of the sear releasing mechanism.

The conventional 1903 Model U. S. Springfield rifle is shown in the drawings for the purpose of illustrating my invention. Such rifle is provided with a stock 1, cocking piece 2, safety lock thumb piece 3, bolt 4, magazine 5 and bolt handle 6 for manipulating the bolt. These elements are unchanged.

A trigger 7 extends from within the guard bow 8 into the chamber 9 thereabove, which chamber encloses the trigger mechanism that connects the trigger with the cocking piece. This chamber 9 is defined by a forward wall 10 that is the rear wall of magazine 5, and by an upper wall 11 below the bolt 4 and the cocking piece. A rear wall 12 and opposed lateral side walls 13, 14 are formed by portions of the stock which is slotted to receive the magazine and trigger mechanism. The bottom wall constitutes extensions of the guard bow 8 and is slotted to pass the trigger.

The cocking piece 2 carries a rectangular block 15 rigid therewith that is formed with a sear notch 16 in its lower side for engagement with sear nose 17. Sear nose 17 is formed on the rear end of sear 18. The use of the designations "rear," "forward," and the like, refer to positions with respect to the muzzle of the rifle, which is at the "forward" end.

The provision of a sear notch and a sear having a sear nose for engagement in the said notch to hold the cocking piece in cocked position is generally old. However in the conventional block formed with the sear notch, the underside slants upwardly in a rearward direction from a point just rear of the sear notch. The underside of the block 15 is horizontal in direction extending away from the notch for a purpose later described more in detail.

The sear 18 is pivotally supported adjacent its forward end on a horizontal pivot 19, and a spiral spring 20 positioned between pivot 19 and wall 10 reacts between the upper wall 11 and a portion 21 of the sear that projects slightly forwardly from pivot 18. This spring functions to yieldably urge the rear end of the sear, including said sear nose 17, upwardly. The upper wall 11 is formed with an opening for the sear nose and through which opening the latter is adapted to project for engagement in notch 16 when the cocking piece is retracted to cocked position. A downward swinging of the rear end of the sear so as to pull the sear nose out of notch 16 will release the cocked cocking piece for firing a cartridge in the firearm.

The trigger 7 is pivotally secured at its upper end within a slot in sear 18 by means of a horizontal pivot 22. This pivot supports the trigger for swinging of the latter about the horizontal axis of said pivot.

Between pivot 22 and the sear nose, and in the same slot in the sear in which the upper end of the trigger is positioned, is a generally vertically extending pin 23 that is reciprocable in an opening 22' (Fig. 10) in the trigger at a point between pivot 22 and the finger engaging portion of the trigger. A spiral spring 24 around pin 23 reacts between head 25 of said pin and the portion of the trigger around the hole through which said pin extends for yieldably urging said head against wall 11 of chamber 9. The trigger itself is offset rearwardly at the point through which the pin 23 extends so that the expansive force of the spring 24 will constantly urge the part of trigger 7 that projects into the trigger guard bow to a forward position in the latter. In this forward position the trigger is ready for a retraction by the trigger finger, and as the trigger is so retracted, a progressively increased force is placed on the sear tending to swing the sear nose downwardly out of engagement with the sear notch in the block 15.

Below pivot 23 a substantial distance is a horizontally elongated member 26 through which the trigger 7 extends, said member being slotted for said trigger, the slot being relatively long horizontally so as to permit appreciable oscillation of the trigger horizontally in said slot. The rear end of the member 26 is pivotally connected by a pivot 27 with the lower end of an arm 28 that extends upwardly from said pivot. This arm 28 is pivotally supported on a fixed pivot 29 near the upper end thereof and a projection 30 extends upwardly from pivot 29. This projection is formed on its forward side with a notch 31 providing an upwardly facing shoulder that is adapted to engage under a projection 32 on the rear end of sear 18. A torsion spring 33 carried on a pin 34 reacts at one of its ends against the rear side of projection 30 for yieldably urging the portion of the arm below pivot 29 against a transversely extending pin 35 that rotatably extends through fixed, spaced, opposed side members 36 secured in chamber 9. These side members also support the ends of pivots 27, 29.

Around pivot 27 is a torsion spring 37 having its opposite ends in engagement with the lower end of arm 28 and with the member 26, said spring being arranged and adapted to yieldably tend to urge the forward end of member 26 downwardly.

The sides of the member 26 are each similarly formed with a horizontal slot 40 where they extend past the trigger, and the lower side of each slot is formed with a recess 41 opening into slot 40, and which recess thus provides a forwardly facing rear edge along one side thereof in the member 26.

The forward closed end of member 26 is slotted and the bottom of the slot is inclined rearwardly and upwardly from the lower edge thereof as indicated at 42 (Fig. 2). This slot in the forward end of said member opens forwardly and is adapted to receive therein a rearwardly projecting pin 43 that is secured rigidly on a downwardly extending projection that is on the forwardly projecting part 21 of sear 18.

The rear end of member 26 carries an upwardly projecting member 44 that is pivoted on said member by a pivot 45, said member being adapted

to rock on said pivot forwardly and rearwardly, but is yieldably held in the forward position by a spiral spring 46 that reacts between the bottom of said member at a point rearwardly of pivot 45 and the member 26.

Below the rear end of member 26 and at a point forwardly of the position of pivot 27 is a cross bar 50 that is yieldably supported for vertical movement on an expansion spring held in an upwardly opening short channel member 51 that is rigidly carried on a horizontally extending lever 52.

This lever 52 is a safety device and its forward end is pivotally supported on a pivot 53 for vertical swinging of the rear end thereof. A spiral spring 54 reacts between the bottom of chamber 9 and an extension of said lever that projects forwardly of said pivot 53 to tend to always urge the rear end of said lever downwardly. Also, the lever is horizontally slotted for said pivot 53, whereby the lever may be moved longitudinally on said pivot.

The rear end of lever 52 extends downwardly through an opening in a rear extension 55 of the trigger guard bow, and is formed with a rearwardly extending lip 56 that is relatively short and which lip normally projects below said extension 55 in a position to be forced upwardly flush with said extension when the hand of the operator grasps the stock with the trigger finger engaging the trigger 1. Only about one finger of said hand will engage said lip, and ordinarily in a normal hand, this will be the middle finger that can easily be extended to free the lip for downward movement of the rear end of the lever 52 without releasing the grip on the stock by the other fingers.

The lever 52 is slotted to pass the trigger 1, the channel member 51 extending between the sides of such slot, and the side members 36 that carry pivots 27, 29 are joined at their lower ends and the portion so connected also extends through the slot in lever 52 to connect with the bottom of chamber 9.

The rear side of the guard bow 8 at about its juncture with the portion thereof that forms the bottom of chamber 9, is slightly thickened, and is transversely drilled to rotatably support therein a hollow sleeve 60 (Fig. 6). One end of sleeve 60 carries a lever 61 that extends upwardly along side the stock adjacent the trigger guard bow.

This sleeve, as seen in Fig. 7, is formed in one side thereof with a generally Z-shaped slot except that the leg connecting the head and foot portions 62, 63 is perpendicular to the latter. A shaft 64 is reciprocable within sleeve 60 and projects from the ends of the latter, one projecting end portion being designated 65 and the other 66. A pin 67 projects from one side of said shaft through the slot formed in sleeve 60, and in the side of shaft 64 opposite pin 67 is a row of recesses 68 adapted to frictionally receive a spring urged detent 69 (Fig. 6). This detent and the recesses are respectively formed to permit longitudinal reciprocation of shaft 66, but to frictionally hold said shaft in adjusted position, and the end of the pin outwardly of sleeve 60 projects into a slot 70 in the upper part of the bow guard (Figs. 2, 6) that prevents rotation of said shaft in any position while permitting said longitudinal movement.

On lever 61 and adjacent to but spaced over sleeve 60 is a projection 71 that extends parallel with sleeve 60 through a passageway 72 formed in the upper end of the rear side of the bow guard.

This passageway communicates with an upwardly opening slot into which extends a pair of depending legs 73 on lever 52 and between which legs said projection 71 extends (Figs. 3 to 6). The passageway through which projection 71 extends is of sufficient size to permit considerable movement of said projection longitudinally of lever 52 when the lever 61 is rotated. This distance is sufficient to move lever 52 forward when lever 61 is moved forwardly, and to move lever 52 rearwardly when lever 51 is moved rearwardly. In the rearward position the lever 61 will have carried the projection 71 a sufficient distance to move the lip 56 on lever 52 to a position extending below the imperforate portion of the extension 55 (Fig. 5) thus blocking upward movement of the lever 52.

Referring back to the pin 35 against which the lower portion of arm 28 is yieldably held: The section of said pin that engages arm 28 also functions as a cam, having a low flat side 80, and a high side 81 and an intermediate flat side 82 that is spaced from the central axis of the pin a distance that is between the longer distance that the high side 81 is spaced therefrom and the distance that the lower side is spaced from the axis (Figs. 3, 4).

One end of said pin carries a disk 84 (Fig. 1) that is rotatably fitted in a recess formed in a plate 85 secured in one of the outer sides of the stock. This disk 84 carries a transversely extending element 86 projecting from the outer side of said disk, which element is easily grasped by the fingers of an operator for turning the disk, thereby rotating the pin 35 to bring one of the several cam surfaces 80, 81, 82 against arm 28. On the plate 85 adjacent the periphery of disk 84 are three spaced marks 87, 88, 89. When links 90 on element 86 is substantially aligned with mark 87, as in Fig. 1, the low side 80 of the cam on pin 35 is against arm 28, and in this position the member 44 on the rear end of member 26 is spaced rearwardly of the main body of sear 18 so as to be spaced below the rearwardly extending projection 32 on said sear. Thus the member 44 performs no function in this position when the various parts are arranged as in Fig. 2 irrespective of how trigger 1 is actuated.

When the disk 84 is rotated to bring line 90 in alignment with the mark 88 (Fig. 10), the intermediate face 82 of the cam section of pin 35 will engage arm 28, and the member 26 will be moved forwardly sufficient to just bring enough of member 44 under the rear end portion 92 of sear 18, and in this position a shoulder 93 on the rear side of the trigger 1 will engage under the forward side 94 of member 44 to cause rotation of the upper end of said member rearwardly when the trigger is retracted sufficiently to cause engagement between said forward underside 94 and said shoulder 93. Also when the member 26 is moved forwardly by said rotation of the cam on pin 35, the notch 31 is moved rearwardly out of engaging relation with the projection 32 of the sear, whereas when the low side 80 of the cam engaged arm 28, the said projection 32 was held in said notch. When line 90 and mark 88 are in alignment a very slight movement of the member 44 by the trigger shoulder 93 will free the member from engagement with the sear, thereby freeing the sear for downward movement and a release of the sear nose from the sear notch, thus releasing the cocking piece.

When disk 84 is rotated to bring line 90 into alignment with mark 89, the high side of the cam on pin 35 will be against arm 28, thus moving the member 26 forwardly still more than when the

side 82 engages said arm. Fig. 4 illustrates the position of the member 44 when the said mark 89 is aligned with line 90. In this position the member must be moved rearwardly a relatively long distance before it clears the rear end 92 of the sear to permit release of the cocking piece 2.

In operation, when the disk 84 on pin 35 is rotated to bring line 90 on said disk into alignment with the mark 87 (Fig. 1), the parts of the trigger mechanism are as seen in Fig. 2, the cocking piece 2 being held in cocked position by the engagement of the sear nose 17 in sear notch 16 of block 15. Upon retraction of the trigger 7 by the trigger finger to the position indicated in Fig. 3, a pin 100 on trigger 7 that extends into slot 40 of member 26 will be carried rearwardly in said slot until it reaches the recess 41. This recess opens upwardly into slot 40, and the upward force of member 50 against member 26 when lip 56 on lever 52 is gripped to stock 1 causes the member 26 to be yieldably swung upwardly about pivot 27 against the force of spring 37. The arrival of pin 100 at said recess will result in such upward swinging and said pin will then be in the said recess as indicated in Fig. 3.

Upon the aforesaid retraction of the trigger 7, the normal position of the middle finger of the hand that carries the trigger finger would be in gripping relation to the lip 56 of lever 52, thus raising the lever and the cross bar 50 until the latter engages the under side of the member 26 at a point forwardly of the pivot 27. The result of this is that the forward end of member 26 moved upwardly and is held in the position indicated in Fig. 3 and pin 100 is adapted to engage the rearwardly facing edges of recess 41 upon a release of trigger 7 for moving member 26 forwardly thereby withdrawing the upwardly facing shoulder of notch 31 from a position obstructing downward movement of sear 17 under the expanding force of spring 24. If, however, the gripping pressure of the finger on lip 56 is released at any time before the projection 32 passes the notch 31, the outer end of member 26 will be free to swing downwardly as the trigger is released, and the cocking piece will remain cocked. Thus should the operator desire to withhold firing after a retraction of the trigger, he merely releases the lip 56, and the trigger may then be safely released without firing the firearm.

The degree of engagement between the sear nose and the sear notch, and the relation between the various pivots and pins and elements of the trigger mechanism are such that after a full retraction of trigger 7, the cocking piece will be released as soon as the trigger has moved forwardly toward its normal position about the thickness of a dime and preferably not more than about the thickness of a dollar. This is relatively important, since too short a distance of movement would produce in the operator an undesirable nervous tension, whereas too great a distance of movement would delay the release of the cocking piece beyond the point of maximum coordination between the nerves and the mental and physical facilities of the operator. The range of from about .05 of an inch to about .15 of an inch in the travel of the trigger from a fully retracted position toward its forward position before the cocking piece is released is satisfactory for the average user, although about .1 of an inch travel is preferred.

To convert the trigger mechanism to the compression firing type in which there is a modified "hair trigger" action, the disk 84 is rotated until

the intermediate flat side 82 is against the lower end of arm 28, in which position the line 90 on said disk is aligned with the mark 88 and the member 86 will be in the dotted position indicated in Fig. 1.

In this position (Fig. 10) the projection 32 on the rear end of sear 18 is out of notch 31, but instead, a fractional portion of the upwardly facing end of member 44 is under the rear lower corner 92 of the main body of the sear 18, hence until this member is moved from under the sear, the sear nose 17 will be in the sear notch 16.

To release the sear nose, the trigger 7 is retracted and this retraction will be resisted only by spring 24 until the shoulder 93 on the trigger engages the lower side 94 of the forward end of member 44. When this engagement occurs, there is a noticeable increase in the resistance, and after this resistance is first noted, a very slight further retraction of the trigger will cause the upper end of member 44 to swing rearwardly about pivot 45 to thereby release the sear nose from the sear notch. The accumulated power in spring 24 will quickly pull the sear nose downwardly and out of the sear notch as soon as the member 44 is disengaged from the sear by the retraction of the trigger.

Where it is desirable to have a prolonged resistance to the withdrawal of the member 44 from its position holding the sear nose in the sear notch, the disk 84 is turned to the point where line 90 is adjacent to mark 89 and in alignment with the latter. In this position the cam section of pin 35 is positioned as indicated in Fig. 4 in which the high side 81 of said section is against the lower end of arm 28. The member 44 is well under rear end 92 of sear 18 when the disk is in the above position.

The retraction of the trigger 7 for releasing the sear nose 17 from the sear notch 16 is the same as when the trigger mechanism is set for providing a hair trigger action, except that a considerably longer travel of the trigger is required after its shoulder engages the member 44 for releasing the member from engagement with the sear. This longer travel is desirable for those that prefer to employ the conventional "trigger squeeze" method for firing the firearm, by which method the trigger is pulled slowly through a relatively long distance under a substantially uniform resistance before the point is reached where the cocking piece is released.

The usual safety lock thumb piece 3 may be used to lock the cocked cocking piece against release when the trigger mechanism is adjusted for compression firing.

In order to lock the trigger mechanism from actuation when the same is adjusted for release firing, the lip 56 is released so as to assume the position indicated in Figs. 1, 2. When in this position and the trigger mechanism is adjusted for release firing as in Fig. 1, and the pin 67 (Fig. 7) is in the end 62 of the slot in sleeve 60. Thus the sleeve 60 is held against rotation and lever 61 is in the full line position shown in Fig. 1. The lever 52 that carries the legs 73 is held against rearward movement by the projection 71 that is on lever 61. In order to rotate the lever 61 rearwardly so as to move the lip 56 to the position seen in Fig. 5, it is first necessary to push end 66 of shaft 64 to the position indicated in Fig. 7 in which position the sleeve 60 can be rotated until pin 67 is in a position to move into end 63 of the slot upon further axial movement of shaft 64 by pushing on the end 66. There are three separate

moves to be made in changing the safety lever 61 from a locked position permitting the swinging of lever 52 as in Figs. 3, 4, to a locked position preventing the swinging of said lever, and vice versa. Thus it is practically impossible for the safety lever to be accidentally moved, once it is locked in one position or the other.

After the cocking piece 2 has been released, the block 15 will ride over the sear nose 17 and will close the opening through which said nose is adapted to extend and will hold the sear nose down until the cocking piece is again cocked. The rectangular form of said block effects this result, which would not be possible with the conventional blocks, the lower side of which is inclined upwardly and rearwardly from the lower end of the sear notch.

The spring 46 that yieldably urges the member 44 to its forward position functions to restore the member to the position indicated generally in Fig. 4 as soon as the rear end of the sear is elevated by cocking of the cocking piece, and spring 20 yieldably urges the sear nose upwardly at all times so as to cause cocking of the cocking piece upon retraction of the latter after each release thereof.

The pin 35 that regulates the characteristics of the trigger action, and which pin has the adjusting disk 84 exposed at one side of the stock for turning, might tend to accidentally rotate during firing of the firearm were it not for a locking element 105 (Fig. 9) carried by the element 86 that is adapted to be received in one of the three notches 106 that are formed in the bottom of the recess in plate 85 (Fig. 8). These recesses are respectively adjacent the marks 87, 88, 89.

The element 86 is supported on disk 84 for reciprocal movement longitudinally of the element 86, there being extensions 107 at the ends of the element that slidably fit in radially extending openings in a rim 108 that is adjacent the periphery of the disk 84. A spring wire 109 held at one of its ends in a groove in the periphery of disk 84 extends across one end of the extension on element 86 for yieldably urging the latter and the locking element 105 toward locked position.

The sides of the element 86 are divergent in direction away from the end that carries the locking element 105, as seen in Fig. 1, for grasping of the element 86 between the thumb and forefinger and to facilitate withdrawal of the element 105 from any one of the notches 106 in adjusting the disk.

This positive requirement for manipulating the element 86 as above described, in order to change the position of the cam section on shaft 35 absolutely precludes any accidental rotation of shaft 35, and yet an adjustment may be quickly effected.

Having described my invention, I claim:

1. In a firearm having a cocking piece, a sear for holding said cocking piece cocked and movable to a position releasing said cocking piece, and a finger retractable trigger; means connecting said sear with said trigger for releasing said sear either at a point during retraction of said trigger or at a point during return of said trigger after its retraction and release thereof and releasably engaging said sear for restricting the release thereof from said cocking piece to one only of the aforesaid points as desired, said means including a spring and further including a member frictionally engaging said sear and movable a predetermined distance under frictional resistance to release said sear at one of said points and means

for varying the said distance said member is movable for effecting said release.

2. In a firearm having a cocking piece, a sear for holding said cocking piece cocked and movable to a position releasing said cocking piece, and a finger retractable trigger; means connecting said sear with said trigger for releasing and sear either at a point during retraction of said trigger or at a point during return of said trigger after its retraction and release thereof and releasably engaging said sear for restricting the release thereof from said cocking piece to one only of the aforesaid points as desired, said means including a spring and separate elements respectively movable into and out of positions obstructing movement of said sear to said position thereof.

3. In a firearm having a cocking piece, a sear for holding said cocking piece cocked and movable in one direction from a cocking piece holding position to a released position disengaged from said cocking piece and vice versa, and a trigger retractable under finger pressure from a normal forward position and spring urged back to said forward position upon release of such pressure; means connecting between said trigger and said sear for yieldably urging the latter in said one direction during retractive and return movement of said trigger beyond a predetermined distance from said forward position thereof, obstructions respectively arranged and adapted to separately hold said sear from movement in said one direction during part of said retractive movement only or during said retractive movement and part of said return movement of said trigger, means actuated by said trigger at a point in its travel beyond said distance for releasing said sear from said obstructions, and manually actuatable means for rendering one or the other of said obstructions inoperative for holding said sear during any movement of said trigger, whereby said sear may be released upon retractive movement of said trigger or upon said return movement thereof as desired.

4. In a firearm having a cocking piece, a sear for holding said cocking piece cocked and movable in one direction from a cocking piece holding position to a released position disengaged from said cocking piece and vice versa, and a trigger retractable under finger pressure from a normal forward position and spring urged back to said forward position upon release of such pressure, a spring connecting between said trigger and said sear for yieldably urging the latter in said one direction during retractive and return movement of said trigger adjacent the maximum retractive limit of said trigger, means for limiting the retractive movement of said trigger, separate sear holding means for separately and releasably securing said sear from releasing said cocking piece during part of said retractive movement only or during said retractive movement and part of said return movement of said trigger, trigger actuated means for releasing either of said separate sear holding means upon said retractive or said return movement of said trigger, and means for rendering one or the other of said sear holding means inoperative for holding said sear whereby the remaining operative sear holding means will be released upon either retractive movement or return movement of said trigger according to which of said sear holding means is operative.

5. A trigger mechanism for a firearm comprising, a cocking piece, a sear movable into and out of engagement with said cocking piece for releasably holding the latter cocked when in engagement therewith, a retractable trigger pivotally

supported on said sear, an element pivotally supported for movement into and out of the path of movement of said sear arranged and adapted to obstruct said movement of said sear out of engagement with said cocking piece when said element is in said path, means on said trigger for engaging said element and for moving it out of said path upon retraction of said trigger, a spring connecting between said sear and said trigger for yieldably urging said sear in a direction out of engagement with said cocking piece upon retraction of said trigger whereby said sear will be released when said trigger so moves said element out of said path of said sear, means supporting said element for bodily movement to a position removing it from engagement with said sear irrespective of its first mentioned movement, said means including a second element movable for releasably engaging said sear for holding it against release during said retraction of said trigger when said first mentioned element is moved

5 to said position and means actuated by said trigger upon return movement thereof after a retraction for releasing said second element from said sear whereby said sear will be free for movement out of engagement with said cocking piece under the influence of said spring.

6. A firing mechanism for a firearm that includes a cocking piece, a movable sear for releasably holding said cocking piece cocked, a retractable trigger supported for oscillatory movement, a rotary cam, separate means movable to and from different positions respectively obstructing release of said sear from holding said cocking piece, means connecting said separate means with 10 said trigger for causing said movement of said separate means, means actuated by rotation of said cam for rendering one or the other of said separate means inoperative for so obstructing said sear.
